SEAL FOR ADVERTISING MATTER

Bernard H. Ziehler, Dayton, Ohio

Application May 15, 1933, Serial No. 671,133

3 Claims. (Cl. 283—6)

This invention relates to advertising devices and means for stimulating trade, and more particularly to a seal attachable thereto for effectually concealing underlying indicia and preventing access thereto.

The use of adhesive trading stamps issued by a merchant to his customers in proportion to the extent of cash sales, and provision of books in which the stamps are affixed which, when the book is filled, are exchangeable for articles of merchandise as premiums to be selected by the customer, is quite old and well known.

More recently there has been used a variation of this plan of trade stimulation wherein different trading stamp books when filled are exchangeable for various premiums which are unknown to the customer until the book is entirely filled, but which are identified by indicia concealed under a breakable seal attached to the book. Such seal is usually attached to the cover of the book which is to be returned to the merchant with the seal unbroken. Various methods of securing such seals have been employed in attempts to prevent tampering or premature exposure of the indicia. By springing the seal and support apart, or by loosening adhesive and by similar methods persons holding the books seek to surreptitiously ascertain the concealed premium identifying indicia, and if the capital prize or one of material value is not identified thereby they lose their incentive to fill the book by further purchase of merchandise.

In the event that the seal, which is usually of paper or similar material, is permanently secured and access can not otherwise be had, resort is had to a powerful light such as that from a picture projecting machine which being transmitted through the otherwise opaque material reveals the underlying indicia.

The present invention pertains to a seal which can not be easily manipulated to expose the concealed matter and which will be resistant to transmitted light, and incapable of being detached without mutilation which will invalidate the book.

The object of the invention is to provide a trade stimulating or advertising device having thereon an indicia concealing seal which is impervious to light and which is attached and secured in such manner as to prevent access to the underlying indicia.

A further object of the invention is to provide such concealing device which will be comparatively small, and hence leave available greater space for display purposes, and which will be inexpensive, capable of being quickly applied,

secure, and incapable of manipulation without first mutilating the attaching device.

With the above primary and other incidental objects in view, as will more fully appear in the specification, the invention consists of the features of construction, the parts and combinations thereof, and the mode of operation, or their equivalents, as hereinafter described and set forth in the claims.

In the drawing wherein is shown the preferred but obviously not necessarily the only form of embodiment of the invention, Fig. 1 is a perspective view of a trading stamp book to which the present invention has been applied. Fig. 2 is a perspective view of the seal removed from the book. Fig. 3 is a detail sectional view. Figs. 4 and 5 are perspective views of the indicia bearing strips unfolded and folded.

Like parts are indicated by similar characters of reference throughout the several views.

While for illustrative purposes the invention is herein illustrated and described as embodied in a trading stamp book it is to be understood that the seal herein shown may be applied to cards, loose sheets or other forms of support upon which it is desired to conceal certain indicia.

In the drawing 1 is a book having the cover 2 and leaves 3. The leaves 3 are provided with spaces 4 to receive adhesive stamps 5.

Each book when issued bears identifying indicia of the premium for which the book is redeemable when filled. To prevent premature ascertainment of the redemption value of the book and thereby maintain the incentive to purchase sufficient merchandise to enable the book to be filled with stamps so obtained, the identification matter is sealed from view.

In the present instance such indicia are concealed beneath a thin metallic leaf 6 folded medially upon itself and disposed about the margin 40 of the cover 2 of the book. The metallic leaf or seal 6 is preferably cemented or otherwise adhesively attached to both sides of the cover 2 or other support, and in addition thereto it is preferably further secured by an eyelet 7 extending 45 through openings 7' in the folded portions of the seal or leaf 6 and through the interposed support 2, and clenched against removal. The indicia to be concealed may be applied to either the supporting portion 2 or to the inner side of the folded leaf or seal, either by printing directly thereon the identifying marks or inscription, or by means of a suitable label interposed between the leaf or seal and the support. However, the preferred method is to print the indicia 9 upon a separate 55

strip of material, which is then folded longitudinally one or more times upon itself with the indicia interiorly. The folded indicia bearing strip 8 is then inserted within the seal leaf 6 and 5 transversely folded collectively with the initial seal leaf about the margin of the cover or support 2 and the ends of the folded strip are secured by the eyelet 7 or other transfixing member which extends through the opposite ends of the folded 10 strip in addition to extending through the ends of the seal leaf and interposed cover 2. The metal leaf resists any attempt to bend or spread it away from the interposed support 2 and is opaque to transmitted light. The insert strip 8 can not be 15 unfolded beneath the seal leaf and surreptitious examination of the concealed matter is effectively prevented.

From the above description it will be apparent that there is thus provided a device of the character described possessing the particular features of advantage before enumerated and desirable, but which obviously is susceptible of modification in its form, proportions, detail construction and arrangement of parts without departing from the 25 principle involved or sacrificing any of its advantages.

While in order to comply with the statute, the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. As an article of manufacture, a booklet having a cover and leaves adapted to receive adhe-

sive stamps and an indicia concealing seal comprising a section of sheet metal folded about and enclosing the margin of the book cover, and extending on opposite sides thereof, an indicia bearing sheet folded longitudinally upon itself 5 with the indicia thereon inturned, said longitudinally folded indicia sheet being again folded transversely about the margin of the book cover on opposite sides of which it extends beneath the sheet metal seal, and an attachment member 10 transfixing the opposite folded portions of the seal and interposed cover of the book, and the folded indicia bearing sheet concealed beneath the seal, said indicia bearing sheet being accessible only by breaking such seal. 15

2. A booklet including a supporting sheet, a mask comprising a sheet of opaque material folded about the margin of the supporting sheet and extending on opposite sides thereof, said mask having its ends fixedly secured thereto at opposite sides of the supporting sheet, and a separate removable indicia bearing member folded about the margin of the support beneath the mask and having its ends secured thereto at opposite sides of the supporting sheet, said indicia bearing 25 member being normally concealed between the support and mask and visible only by removal of the mask.

3. A sales booklet including a support, a seal leaf mask folded about the margin of the support 30 and extending on opposite sides thereof, and a separate indicia bearing strip longitudinally folded upon itself with the indicia innermost, said folded strip being again transversely folded about the margin of the support and extending on opposite sides thereof beneath the folded seal leaf, and attachment means transfixing the portions of the seal leaf and folded indicia strip on opposite sides of the support. 35
